CLAIM

The ornamental design for a golf club head for a putter, as shown and described.

DESCRIPTION

FIG. 1 is a front view of a golf club head for a putter showing our new design; and,

FIG. 2 is a top perspective view thereof.

The solid black shading represents a contrast corresponding to a change in appearance due to material, texture, or color. The broken line showing that is immediately adjacent to the shaded area represents an unclaimed boundary and forms no part of the claimed design. The broken line showing of the remainder of the golf club head for a putter is for illustrative purposes only and forms no part of the claimed design.
